UNITED STATES PATENT OFFICE.

ALEXIS TETRAULT AND EDWIN C. POHLE, OF BOULDER, COLORADO.

DRY-ORE-CONCENTRATING TABLE.

No. 798,843.

Specification of Letters Patent.

Patented Sept. 5, 1905.

Application filed December 13, 1904. Serial No. 236,717.

To all whom it may concern:

Be it known that we, ALEXIS TETRAULT and EDWIN C. POHLE, citizens of the United States, residing at Boulder, in the county of Boulder 5 and State of Colorado, have invented certain new and useful Improvements in Dry-Ore-Concentrating Tables; and we do hereby declare the following to be a full, clear, and exact description of the invention, such as will enable others skilled in the art to which it appertains 10 to make and use the same.

Our invention is directed to the production of an improved table separator and concentrator for ores in the condition of dry powder while being subjected to a reciprocating knocking movement within a chamber of the 15 table under the suction and exhausting force of air therein.

The following description, read in connection 20 with the accompanying drawings, will enable any person skilled in the art to which our invention relates to understand its nature and to practice it in the form in which we prefer to employ it; but it will be understood 25 that our invention is not limited to the precise form and construction herein illustrated and described, as various modifications and changes may be made without exceeding the scope of the claims or the invention there- 30 in set out.

Referring to the drawings, Figure 1 represents in top view an ore-separating table having a chambered top surface upon and within which the separation of the heavier from the 35 lighter or waste particles are effected by the combined reciprocating bumping movements of the table and the force of air-currents drawn by suction over the inclosed surface of the table. Fig. 2 is a vertical longitudinal 40 section showing the table-chamber and its air-suction connections, taken on the line 1 1 of Fig. 1, showing the suction device in elevation. Fig. 3 is a vertical transverse section taken through the chambered table on the 45 line 2 2 of Fig. 1. Fig. 4 is a vertical transverse section taken through the chambered table on the line 3 3 of Fig. 1, showing the openings through which the lighter particles are carried from said chamber into the 50 exhaust. Fig. 5 shows the openings at the end of the table through which air is drawn into its chamber. Fig. 6 is a detail in section of the air-suction pipe, which connects the chambered table with the suction device and the 55 valve by which the volume and force of the suction is regulated. Fig. 7 is a transverse

section through the suction-pipe and its regulating-valve.

The table 1, preferably of oblong rectangular form, is constructed with a smooth surface and a closed cover 2, forming a chamber 3, the area of the table within which the separation and concentration of the ore is effected in a manner and by means which constitute my invention. Upon a suitable foundation-frame are pivotally mounted in bearings 4 rocker-supports 5, arranged, preferably, to support the four corners of the table, while the latter has bearings 6 to receive the supports and accommodate the reciprocating movements of the table. Air is preferably drawn into the table-chamber at one end through openings, (seen in Fig. 5,) and from this end the table inclines downward to its other end, as seen in Fig. 2, its pair of supports for this purpose at its highest end being longer than the pair of supports at its lowest end. The table-mountings are preferably arranged to allow the table to be reciprocated in a direction at right angles to the direction of the air-currents within and through the table-chamber, and for this purpose the delivery of the values or heavier particles of ore is effected at one side of the table and the means for effecting its movements 85 are arranged at its opposite side. These means may consist of a power-driven shaft 8, having an eccentric 9, a connecting-rod 10, from which, by suitable means, is connected to the table, so that the rotation of the eccentric gives reciprocating movements to the table. The eccentric-rod connections may be by bow-spring 11, links 12, and screw-rod 13 engaging a bracket 14 on the table, such engagement being made adjustable by nuts 15. 90 An abutment 16, depending from the table, is adapted to engage an abutment 17, rising from the foundation-frame, to give a bumping action to the table movement.

We prefer to mount the feed-hopper 18 at 100 that side of the table to which the reciprocating power is applied and at the corner of the end at which the air is drawn into the chamber, so that the ore will pass from the hopper upon the table at right angles to the direction 105 of the air-currents which are created from the opposite end of the table, as we will now state. At and upon this end of the table an exhaust-chamber 19 is transversely arranged, so that its inner wall has communication with 110 the table-chamber by openings seen in Fig. 4. This chamber is formed by a narrow box on

a level with the table which forms its bottom, and the suction device drawing the air from it produces therein a partial vacuum, the effect of which is to cause the currents to be 5 spread and be diffused within the table-chamber to pick up the lighter particles from the powder and carry them out.

An air-suction device 20 is connected by a pipe 21 to that end of the vacuum or exhaust-chamber at the side of the table at which the power is applied, and this pipe is connected to said chamber by a suitable flexible connection 22 to accommodate the movements of the table and maintain the suction connection. 15 The suction device may be of any suitable construction adapted to be driven by power, and to regulate the force and volume of the air-currents drawn through the table-chamber we provide the pipe which connects the 20 suction device with the table exhaust-chamber with an air-inlet 23, controlled by a valve 24, which may be a cap carried by a screw-stem 25, by which the cap may be adjusted to increase or to diminish the area of said air-inlet to increase or diminish the force of the 25 air-suction in the exhaust-chamber and correspondingly increase or diminish the volume and force of the air-currents drawn into and through the table-chamber to suit the character 30 of the ore to be separated, as no two ores are of the same specific gravity. By raising the valve the force of the volume of the air-currents drawn into the chamber over the table is weakened and lessened, and by closing 35 the valve a greater and stronger volume of air is drawn in the table-chamber through and over the powder.

As seen in Fig. 3, the table-chamber has a greater depth at its side where the ore is received from the hopper than at the delivery side, and the purpose of this is to facilitate the separation of the finer substances and cause them to be carried by the stronger air-currents toward the exhaust-chamber, while 40 the heavier substances by reason of the bumping action of the table gradually move across its surface to its delivery side under the separating action of air-currents of less force. As the pulp spreads on the table it takes less room 45 and the air-currents have better effect in taking up and carrying off the dust and lighter particles which come with the values from the crusher or pulverizer. This separating action is aided by the inclination of the table, which 50 by gravity under the bumping movement of the table causes the lighter substance to be thrown to the surface and kept in motion to receive the full effect of the air-currents carrying it into the exhaust-chamber, the heavier 55 substance moving unaffected by the air-currents across the table to the delivery-opening, the suction force from the exhaust-chamber picking up the silica and lighter material and collecting it in said exhaust-chamber, from 60 which it is drawn into and forced from the 65

suction device. For this purpose we provide openings, seen in Fig. 4, and which we prefer to make in the form of a slot or slots 26, opposite the pipe of the suction device, to cause a greater volume of air to be drawn 70 through the table-chamber along its feed-hopper side, where the ore is thickest on the table, while other smaller openings 28, extending to the delivery side of the table, cause a less volume of air-currents to be drawn 75 through the table-chamber over the thinner spread of the ore. Coöperating with these air-exits from the table-chamber into the exhaust-chamber, we provide air-inlet openings at the other or highest end of the table-chamber 80 in the form of slots and perforations 29, the perforations being preferably next to the hopper side of the table and the slots 30 extending toward the delivery side of the table, whereby the light substances are caused to 85 travel in a diagonal course in the chamber to the suction corner thereof and allowing the concentrates to spread on the table, as indicated by the dotted arrows in Fig. 1.

We prefer to make that section of the table-chamber cover next the delivery side of the table of glass 31 to allow inspection by the operator of the air-separating force within the chamber, so that he may regulate the force of the air-currents by the valve to remove only the lighter substances from the pulp. 90

From the foregoing description it will be seen that in the employment of the concentrating chambered table the separation is effected by the reciprocating bumping action of the table, by air-currents produced by suction through the table-chamber, by the action of an exhaust-chamber having communication with a suction device and with the table-chamber, and by the downward inclination of the table-chamber from its air-inlet end to the suction device; but while these several agencies are conjointly effective the two primary agencies in the operation are the reciprocating bumping movements of a chambered table and the production of air-currents within and through the table-chamber, whereby to carry off from said table and out of its chamber the waste or lighter substance of the pulp, leaving the concentrates or values to be delivered from the table by its movements at right angles to the direction of the air-currents, which are admitted at one end of the table, crossing the travel of the pulp on the table and passing out through the suction device. In this operation an important feature is the provision of an exhaust-chamber between the suction device and the table-chamber and communicating with both, having the effect of spreading the air-currents within the table-chamber and partially causing them to have an oblique direction from the inlet end of the table to its outlet end. While this exhaust-chamber adds to the efficiency of 105 110 115 120 125 130

the air separation, obviously the chambered table and the suction device, under the reciprocating bumping of the table, will cause the separation of the lighter stuff from the values and the delivery of each in different directions from the table.

It is important to note that the location of the valve in the pipe of the suction device causes the latter to draw air with more or less volume from said pipe-opening directly into the suction device, and thereby causes greater or less suction force in the exhaust-chamber, creating therein a partial vacuum, according to the force of the suction, and it is this exhausting of the air from said chamber that causes the air-currents drawn therein from the separating-chamber to be spread over the table-surface and to be drawn through said chamber with more or less force controlled by said valve.

While the table is described as having a bumping movement, and which is preferred, obviously a quick reciprocating movement would be effective for shaking up the lighter particles and dust to be carried off by the suction device.

We claim—

1. In a dry concentrator, a quadrilateral smooth-surfaced table, a cover therefor supported at a distance therefrom to form a chamber leaving openings across three edges of the table the openings at two of said edges being for the inlet and for the outlet of air-currents, the other for the discharge of the concentrates, a closure for the fourth edge of said table-chamber, a feed-hopper opening into the table-chamber on its closed side, means to draw air into, through and from said chamber between the feed-hopper and the delivery-opening and means for imparting reciprocating bumping movements to said table.

2. The combination of a quadrilateral smooth-surfaced table, a cover therefor supported at a distance therefrom to form a chamber leaving openings across three edges of the table, a closure for the fourth edge thereof, a casing forming an exhaust-chamber extending across the openings at one end of the table-chamber, means to draw air therefrom, a feed-hopper opening into the table-chamber on its closed edge, and means for causing reciprocating bumping movements to said table.

3. The combination of a quadrilateral smooth-surfaced table, a cover therefor supported at a distance therefrom to form a chamber leaving openings entirely across three edges of the table, a closure for the fourth edge thereof, a casing forming an exhaust-chamber extending entirely across the openings at one end of the table, means connected to that end of said exhaust-chamber next to the closed edge of said table-chamber to draw air into, through and from the table-chamber, a feed-hopper opening into the table-chamber

on its closed edge, and means for imparting reciprocating knocking movements to said table-chamber.

4. In a dry concentrator, a smooth-surfaced table, a cover therefor forming a top chamber, leaving openings across three edges of the table, a closure for the fourth edge thereof, a casing forming an exhaust-chamber extending across the openings at one end of the table, a pipe connected to one end of the exhaust-chamber, means to draw air therefrom connected to said pipe, an open-ended pipe rising from the latter, a valve controlling said open-ended pipe for regulating the volume and force of the air-currents, a feed-hopper opening into the table-chamber at its closed edge, and means for causing reciprocating bumping movements to said table.

5. In a dry concentrator, the combination of a table, a cover therefor forming a top chamber, a casing forming an exhaust-chamber across the end of said table having openings communicating with the table-chamber, a suction device, a flexible pipe-section connecting the suction device and the said transverse end chamber, the cover of said table leaving air-inlet openings for the table-chamber, means for imparting to said chambered table reciprocating bumping movements at right angles to the course of the air-currents entering the table-chamber, and means for feeding powdered ore into the table-chamber.

6. An ore-concentrating table having a smooth surface, a cover therefor forming a top chamber leaving air-inlets at one end, and air-outlets at its opposite end, the third edge of said chamber being closed, and its opposite fourth edge delivering the concentrates, a feed-hopper opening into said chamber at its closed edge, means to draw air into, through and from said chamber, and means for causing said table to have reciprocating bumping movements.

7. In a dry concentrator, the combination of a smooth-surfaced table, a cover therefor forming a top chamber leaving openings along three edges of said table, the openings along one edge forming air-inlets, the openings along the opposite edge forming air-outlets, the openings along the third edge for the delivery of the concentrates, a closure for the fourth edge of said table-chamber, a casing forming an exhaust-chamber carried by said table into which said air-outlets open, a feed-hopper opening into the table at its closed edge, a suction device connecting said exhaust-chamber, and means for causing said chambered table to have reciprocating bumping movements.

8. A dry-ore-concentrating table having a smooth surface, a cover therefor forming a top chamber one edge of which is closed, its three other edges being open, a feed-hopper communicating with said chamber at its closed edge, its opposite open edge delivering the

concentrates, means having connection with the end of the table at its closed edge for drawing air into and through said chamber from one open edge of the table through its 5 opposite open edge across the path of the moving powder.

9. A dry-ore-concentrating table having a smooth surface, a cover therefor forming a top chamber, a feed-hopper opening into said 10 chamber at its closed edge, a pair of rocker-supports for each end of the table, one pair having a greater length than the other pair, means having connection with the lowest end of the table-chamber for drawing air-currents 15 into and through it from its highest open edge across the path of the moving powder, and means for causing said chambered table to have sidewise bumping movements.

10. The combination of a smooth-surfaced 20 table, a cover therefor forming a top chamber, a pair of rocker-supports for each end of the table, one pair having a greater length than the other pair, a feed-hopper at one side in communication with said table-chamber, 25 said table-cover having a delivery-opening at that side opposite the feed-hopper, means for causing said chambered table to have a side- wise bumping movement, and means having connection with the lowest end of the table- chamber for drawing air-currents into and 30 through it from the highest end of said table-chamber across the path of the moving powder.

11. The combination of a smooth-surfaced table, a cover therefor forming a top chamber, a feed-hopper at one side in communication 35 with said table-chamber, said cover having a delivery-opening at the opposite side of said chamber, a casing forming an exhaust-chamber carried by said table and having communication with the table-chamber, a 40 suction device for causing air-currents to be drawn into and through said table and said exhaust-chamber, a pipe open at its upper end and connecting said exhaust-chamber with the suction device, a valve controlling said 45 open pipe, and means for causing said chambered table to have reciprocating bumping movements.

12. A concentrating smooth-surfaced table, 50 a cover therefor forming a top chamber,

means for causing said table to have bumping movements, a suction device for causing air-currents to be drawn into and through the table-chamber, a casing forming an exhaust-chamber carried by the table having communication with the suction device and with the table-chamber, a valve for controlling the force of the suction within the exhaust-chamber, a feed-hopper opening into one side of the table-chamber, said table and its cover 60 providing air inlet and outlet openings and an opening for the delivery of the concentrates.

13. A concentrating smooth-surfaced table, a transparent cover therefor forming a top chamber, a feed-hopper opening into said 65 chamber, a casing forming an exhaust-chamber across one end of said table-chamber and having communication therewith, a suction device connected with said exhaust-chamber for causing air-currents to be drawn into and 70 through said table-chamber and into and through said exhaust-chamber, and means for causing reciprocating movements of said table.

14. A dry-ore-concentrating table having a smooth surface, a cover therefor forming a 75 top chamber, a feed-hopper opening into said chamber at its closed edge, a casing forming an exhaust-chamber across one end of the table-chamber means for imparting to said chamber reciprocating bumping movements, the 80 said table-chamber having a plurality of air-inlet slots and perforations along one edge, the said casing having a slot and perforations in communication with the table-chamber, the air-inlet slots and the slot in the exhaust-chamber 85 having diagonal relation relative to the table-chamber, and a suction device arranged to communicate with that end of the exhaust-chamber next the closed edge of the table-chamber, whereby air-currents are drawn into 90 the table-chamber diagonally across the path of the moving powder.

In testimony whereof we have signed our names to this specification in the presence of two subscribing witnesses.
